UNITED STATES PATENT OFFICE.

HEINRICH SOMMERFELD, OF CANTON, KANSAS, ASSIGNOR OF ONE-HALF TO
HARRY C. LEWIS, OF KANSAS CITY, MISSOURI.

CAR-COUPING.

SPECIFICATION forming part of Letters Patent No. 468,311, dated February 2, 1892.

Application filed August 10, 1891. Serial No. 402,261. (No model.)

To all whom it may concern:

Be it known that I, HEINRICH SOMMERFELD, of Canton, McPherson county, Kansas, have invented certain new and useful Improvements in Car-Couplers, of which the following is a full, clear, and exact description, reference being had to the accompanying drawings, forming a part hereof.

My invention relates to the couplings of railway-cars; and the objects of my invention are to produce a car-coupling which shall be simple, strong, and durable in construction, which shall be adapted for application to both passenger and freight cars, and which shall be automatic in its action and capable of forming a permanent and strong connection between the cars of a train; furthermore, to produce a car-coupling which shall be so constructed as to avoid all necessity of the operator entering between the cars either in coupling or uncoupling the same, thus avoiding the danger to life and limb heretofore encountered during such operations.

To the above purposes my invention consists in certain peculiar and novel features of construction and arrangement, as hereinafter described and claimed.

In order that my invention may be fully understood, I will proceed to describe it with reference to the accompanying drawings, in which—

Figure 1 is an under side plan view of the adjacent ends of two railway-cars with my improved coupling applied thereto. Fig. 2 is a detached perspective view of one of the coupling-heads and its connected lever for moving the said head out of coupling position, the draw-bar, and its immediate operative connections.

In said drawings, 1 and 2 designate the bodies of two railway-cars, the body 1 being that of a passenger-car and the body 2 that of a freight or baggage or other similar car. To the under side of each of these car-bodies at each end thereof are bolted, as at 6, two parallel longitudinal beams or timbers 3, to the under sides of the outer ends of which is bolted, as at 5, a strong metal cross-plate 4. Between the two timbers or beams 3, at the inner parts of the same, is placed a thrust-plate 7, the rearwardly-extending ends 8 of

which are bolted, as at 8, to the inner sides of the said timbers or beams 3. The usual draft-rods 9 are bolted at their outer ends, as at 10, to the cross-plate 4, and this plate is provided at one side of its middle with an upwardly-extending stop 11. The stem of the draw-bar 12 extends through the thrust-plate 7 and is surrounded behind and in front of said thrust-plate, respectively, with strong spiral springs 13 and 14, the outer end of the spring 13 bearing against a nut 15, which is screwed upon the inner end of said stem, and the outer end of said spring 13 bearing against the inner side of the thrust-plate 7. The inner end of the spring 14 bears against the outer side of the thrust-plate 7, while the outer end of said spring 14 bears against the inner end of the enlarged portion of the draw-bar 12. A stud 16 depends from the under side of the draw-bar 12 and is designed to come into contact with the inner edge of the cross-plate 4, if excessive pulling strain be brought to bear upon said bar, and thus prevent the draw-bar from being pulled entirely out of the car. To the inner side of one of the timbers or beams 3 is secured a stout leaf-spring 17, the inner end of which is retained in position against said side of the beam by a strong retaining-plate 18, and the outer end of which spring presses laterally against the corresponding side of the draw-bar 12, the tendency of the spring 17 being to force the draw-bar laterally against the stop 11.

Upon the outer end of each draw-bar 12 is formed or suitably secured a draw-head 19, the outer portion of which is formed with two jaws 20 and 21. The jaw 20 is of approximately U or hook form, the inner portion of said jaw extending horizontally and somewhat laterally from the body of the draw-head and its outer end curving inwardly, as shown. The companion jaw 21 is much shorter than the jaw 20 and extends horizontally and laterally from the body of the draw-head, an open space or mouth thus intervening between the two jaws. Each jaw 21 is formed at its outer end with a transverse opening 22, which is designed to receive a detachable hook 23, the said hook 23 being each secured to the outer or opposite end of a chain 24, and each of said chains being secured at its inner

end to the under side of the car-body by a pin or bolt, as at 25. It will thus be seen that this arrangement is such that should the draw or coupling heads become accidentally disconnected the chains 24 will prevent a total separation of the two cars, and it will also be seen that while the train is rounding curves the chains 24 will be drawn taut and will hold the coupling-heads together and prevent all possibility of accidental uncoupling at such times.

Upon the opposite side of each coupling-head from that from which the jaw 21 extends is formed or suitably secured an eye 26, 15 to which is secured the outer end of a chain 27. If the car be a passenger-car, as 1, the opposite end of this chain 27 is connected to the lower end of a lever 28, which is pivoted, as at 29, upon the outer end of the platform 30 of 20 the car at one side thereof. If the car be a freight-car, as 2, the chain 27 extends around a pulley or sheave 31, which is journaled in a suitable bracket 32 at one side of the end of the car, and the inner end of said chain is 25 connected to one end of an operating-lever 33. This lever 33 is pivoted, as at 34, in a bracket 35, bolted or otherwise firmly secured to the bottom of the car near one side thereof. This lever 33 works horizontally beneath a 30 stop-bar 36, having a shoulder 37 upon its outer part and secured at its inner end to a bracket 38, which is bolted or otherwise firmly secured to the bottom of the car near one side thereof. It will thus be seen that the lever 33 is located adjacent to one side of the car and in such position as to be readily reached 35 by an operator standing at the side of the car. Now when it is desired to couple two cars the said cars are simply brought together, 40 the springs 17 automatically forcing the hooked jaws 20 of the coupling-heads 19 over and into locking engagement with each other. When the cars are to be uncoupled, the operator (in the case of a passenger-car) mounts 45 the platform 30 and throws the upper end of the lever 28 inward, and thus, through the medium of the chain 27, moving the coupling-head laterally out of coupling position against the action of the spring 17. If the car be a 50 freight-car, when it is desired to uncouple the attendant or operator stands at one side of the car and reaching beneath the car-body draws the free end of the lever 33 outward. This movement of the lever, acting through

the chain 27, moves the coupling-head 19 laterally out of coupling position against the spring 17, and the cars can then be readily drawn apart. The coupling-heads are held in uncoupled position by the shoulder 37 on the stop-bar and by a similar shoulder 39 on a stop-bar 40, which is secured to the platform of the passenger-car. In either case it will be seen that there is absolutely no necessity for the operator or attendant to pass between the cars either while such cars are being 55 coupled or uncoupled, and it will also be seen that the coupling operation is entirely automatic. The outer extremities of the jaws 21 of the coupling-heads 19 are preferably formed with horizontal recesses 40 to receive the links 70 of cars having the ordinary link-and-pin couplings, and said jaws are also preferably provided with vertical openings 41 to receive the pins of such couplings.

This improved coupling is strong, durable, 75 and simple and inexpensive in construction, is not liable to accidental uncoupling, and is easily and quickly operated.

Having thus described my invention, what I claim as new therein, and desire to secure by 80 Letters Patent, is—

1. An improved automatic car-coupling comprising a laterally-movable coupling-head having a hooked coupling-jaw and a laterally-extending companion jaw, a chain connected 85 to the hooked jaw, a lever pivoted upon the car and connected to said chain, and an opening in the companion jaw designed to receive a chain connected to the opposite car, substantially as set forth.

2. An improved automatic car-coupling comprising a laterally-movable spring-pressed coupling-head, a chain connected to said head, a sheave for said chain, secured beneath the car-body between the lever and the head, 95 a lever connected to said chain and pivoted under the car-body near one side thereof, and a stop-bar secured beneath the car-body adjacent to the said lever and having a shoulder to be engaged by said lever, substantially 100 as set forth.

In testimony whereof I affix my signature in presence of two witnesses.

HEINRICH SOMMERFELD.
